BOTTLE CAPPER

Filed Feb. 1, 1928.

Inventor:
Harold G. Rice.

By Fisher, Towle, Clapp & Sons, Utica.

UNITED STATES PATENT OFFICE

HAROLD G. RICE, OF CHICAGO, ILLINOIS

BOTTLE CAPPER

Application filed February 1, 1928. Serial No. 251,074.

My invention relates to bottle cappers and more especially to novel means for limiting the upward movement of the operating handle or lever after the lever is depressed by hand to apply a cap to a bottle and then released, and for locking the rider and capper head in adjusted position to suit bottles of certain heights until it is desired to change the adjustment for bottles of different sizes 10 or height and also to prevent the lever from swinging up to a vertical position when released from the capping position in such a manner to disengage the segment from the rack bar or release the same from operative 15 engagement with the frame, thus preventing the accidental displacement of the rider from its adjusted position and the dropping thereof on the frame.

The device is associated with a bottle capper of the type covered by my prior Reissue Patent No. 15,222 of November 8, 1921, and the structure shown in my Patent No. 1,678,303 of July 24, 1928, embodies a further improvement in the means shown in the latter patent for raising the operating lever to an elevated position after the lever is depressed as by hand to apply a cap to a bottle and then released, and for normally retaining the lever in a raised position so that the same 20 is in an operative raised and convenient position for use in applying caps with the advantages above pointed out.

Aside from the improvements in the construction of the rider and the raising means, shown in the above referred to patent No. 1,678,303 for automatically raising the handle when the operating handle is depressed to apply a cap to a bottle and then released to raise the same, which, however, was not shown in my prior reissue patent, the invention consists 25 in the novel locking device for the rider and capping head associated with the raising means and lever, said lock being adapted to hold the rider and capping head at a desired height regardless of how fast the device is operated or how roughly it is handled. It also may be instantly set and will stay set without jarring loose during the operation of the 30 capper but permit an adjustment of the cap-

ping head for shorter or higher bottles in an instant.

The device also possesses all of the other advantages referred to in my prior Patent No. 1,678,303 above noted and the invention 55 consists of the combination of the locking device therewith.

With the above and other objects in view, the invention consists in certain novel combinations and arrangement of parts, the relations of which will be more thoroughly established in the following description particularly emphasizing and pointing out the same.

In the accompanying drawings:—

Fig. 1 is a side-elevation of a bottle capper 65 equipped with the novel locking device.

Fig. 2 is a fragmentary horizontal sectional elevation taken on the section line 2—2 of Figure 1.

Fig. 3 is a fragmentary vertical sectional 70 elevation showing the manner of releasing the locking device for freely sliding the rider and capper head to secure an adjustment for bottles of different heights, and

Fig. 4 is a fragmentary vertical sectional 75 view taken on the section line 4—4 of Figure 1.

Referring to the drawings in detail, a bottle capper of the type shown in my prior patents above referred to is illustrated. It consists of a frame including a base or base plate 4 adapted to be anchored to a work bench or table and having sides 5 bent upwardly therefrom. The frame proper is of bowed formation and has sides 6 anchored at their lower 80 ends to the sides 5 of the base and preferably offset outwardly for this purpose but left flat, as indicated at 7. The portions 6 are preferably pressed in concavo-convex cross section with the convex walls outwardly and 85 their upper portions brought together and connected at suitable points as by means of rivets 8. The upper portions are straight and flat and rectilinear and provided at their coacting edges with rack-teeth forming 90 operative means for engagement with the inner end of the operating lever usually in the form of a segment as will be later described and taking the form of a rack bar 9.

Slidably mounted on the rack bar consti-

tuted by the upper portion of the frame is a 5 rider or slide 10 preferably in the form of a relatively flat rectangular sleeve and fashioned from a single plate formed into a rear wall and sides having extensions 11 suitably spaced apart as by a notch 12 in the lower edge of one extension defining an inner wing prolonged transversely of the rider into engagement with the other extension, and the 10 second extension having a notch at its upper edge, while the sides are provided at their forward edges and at their upper ends with inturned lugs 13 having their free ends abutting intermediately of the width of the thickness of the rider above the extensions. The 15 space defined by the rear wall, the sides, and the inner wing of the rider accommodates the rack bar so that the rider may move up and down thereon.

20 A lever 14 is pivoted at 15 so as to fulcrum the same between the extensions 11 and as shown, the handle preferably has its outer or capping portion shaped from a bent piece of metal to fit the contour of the hand in grasping the same. An inner portion 16 comprising a pair of plates riveted between the sides of the portion 14 as indicated at 17 and their inner edges formed with co-acting teeth providing a segment 18 meshing with the rack 9.

25 30 The inner rivet 17 has its head projecting to form a shoulder 19 facing toward the rack bar for a purpose to be hereinafter pointed out. The capping head 20 is carried by the extensions 11, being preferably riveted to reduced downward extensions thereof extended through slots in the end or top wall of the head, as indicated at 21. This capping head is designed to receive a rubber washer or cushion ring 21' to give resiliency to the capping operation, and the top of the capping head serves to limit the downward swing of the lever 14 when depressed by engagement with the shank thereof.

35 40 The pivot 15 is in the form of a double headed rivet and the extension 11 on one side is depressed on both sides around the rivet heads so as to fix the rivet in a mounting for a dog, which may be in the form of an angular cross arm or bell crank lever 22, the heads 45 setting in the depressions and the pivot 15 forming a fulcrum on the extensions 11. The dog or arm is located outwardly of one extension 11 and retained in position by the enlarged headed end of the pivot 15 at that side. The forwardly extending arm of the 50 dog has an angular portion 23 provided with a notch in its upper edge to form a hook extending outwardly for connection of one end of a contractile coil spring 24 thereto, the opposite or lower end of the spring being 55 anchored to the rider 10 adjacent to its bottom edge as by hooking the spring through an apertured ear or lug 25 stamped or pressed and bent outwardly from the bottom edge of 60 said side or extension 11 of the ride as clearly

indicated in Figures 1 and 4. The same arm of the dog has a lateral inward projection or lug 26 which is designed to engage in back of the rider above and on top of the same extension 11 to limit the pivotal movement of the cross arm or dog under the tension of the spring 24 and the free end of the rearwardly extending arm has a lateral inward projection or lug 27 at its bottom edge which is designed to engage beneath the shank of the handle or lever 14, whereby the lever is held in a raised position under the action of the spring limited by the extension 26, as indicated in Figure 1.

65 The cross arm or dog is provided intermediately above the pivot 15 with an inwardly offset and upwardly extending notched ear 28 against the inner face of which is pivoted as at 29, a locking member or pawl 30 which has its free end recessed at the bottom as indicated at 31 to provide an extending finger 32 at the top to engage the shoulder 19 and over the rivet 17 when the handle is in a raised position slightly inclined upwardly but substantially horizontally, as shown. This engagement is maintained with sufficient friction to keep the pawl in its engaged position but to limit the upward movement of the lever when the rider is once adjusted on the rack bar so as to prevent the handle from continuing in its upward movement when released from the capping position after being depressed, or from flying up to a vertical position and disengaging the segment from the rack bar, thereby preventing the rider from accidentally sliding downward on the rack bar or frame when once adjusted to a position to accommodate bottles of a certain height. This device constitutes a lock for the rider and capping head which holds the head at the desired height regardless of how fast the device is operated or how rough it is handled. The lock is set by a push of the thumb to engage its recessed end with the shoulder of the inner rivet 17 and stays set in such a manner that no amount of jarring can loosen it. However, it may be readily displaced from the shoulder of the rivet head and raised to the dotted line position shown in Figure 1 so that the handle may be swung upwardly for disengaging the segment from the rack bar as clearly shown in Figures 1 and 3, whereby the device may be adjusted for accommodating shorter or higher bottles. This may be done in an instant so that the capping head will properly apply the caps.

70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

out interference or obstruction by the capping head or the handle swinging down as in devices not provided with the raising means. Obviously, this arrangement obviates the necessity of raising the lever by hand after a cap is applied to a bottle and leaves both hands of the operator free for other service. When a cap is being applied, the bottle is mounted on the base 4, so that the neck of the bottle will be beneath the capping head, a cap having been previously placed thereon. The operator then presses down on the lever 14 and applies the cap to the bottle, owing to the downward movement of the rider by 15 rocking of the segment 18 on the rack 9. During the downward movement of the lever the shank thereof engages the extension or lug 27 and rocks the cross arm or dog 22 on the pivot 15 or with said pivot, if desired, in the extensions 11 owing to the fact that the pivot 15 is common to the fulcrum of the lever and raises the forward arm to stretch or extend the spring 24 against its tension and at the same time moving the extension 26 away from the top of the extension of the rider.

Upon releasing the pressure from the lever 14, the spring 24 will react and cause the extension 27 to engage the lever and raise it to an operative position slightly above horizontal, which movement will swing the rack at the inner end of the lever down and raise the rider until the extension 26 contacts with the rider at the top edge of one extension 11 but will not cause the lever to be swung to its upward limit or to a vertical position which would result in accidental disengagement of the segment from the rack bar and the sliding of the rider out of its adjusted position. However, this movement is permitted provided the lever is manually raised but not when the pawl or locking member 30 is in engaged position as shown in solid lines in Figure 1. This movement is only permitted when the locking member or pawl is disengaged from the shoulder 19 and the handle may then be swung to the dotted line positions shown in Figures 1 and 3 so as to permit quick adjustment of the rider for shorter or higher bottles. In the position in which the extension 26 contacts with the rider, the capping head will be elevated automatically and removed or raised away from and above the bottle, thus obviating the possibility of the lever dropping down and obstructing the work by interfering with the free insertion of the bottles or caps and requiring manual elevation thereof.

By reason of the cross arm 22 being limited in its movement on the pivot 15 of the lever 14 to a horizontal position, the lever 14 will be supported in a horizontal position for convenient use. It will also be apparent that the lever 14 may be swung upwardly to a substantially vertical position from the

substantially horizontal position in which it is supported by the cross arm and spring, to disengage the teeth of the segment 18 from the teeth of the rack bar 9 to permit free sliding movement of the rider 10 over the teeth of the rack bar of the frame, whereby quick initial adjustment of the rider and capping head to bottles of different sizes, may be obtained. It is, of course, to be understood that the upward swing of the lever 14 is independent of the cross arm 22 away from the supporting lug or extension 27 while the cross arm is held against movement under the tension of the spring 24 by engagement of the lug or extension 26 with the rider 10.

While I have shown and described my invention in a preferred form, I am aware that various changes and modifications may be made without departing from the principles of my invention, the scope of which is to be determined by the appended claims.

I claim as my invention:

1. A bottle capper comprising a frame, a rider slidable on the frame, a lever pivoted on the rider and engaging the frame to reciprocate the rider, a capping head carried by the rider, means for resiliently urging said lever toward a raised position and means to positively limit the upward movement of the lever below a substantially vertical position.

2. A bottle capper comprising a frame, a rider slidable on the frame, a lever pivoted on the rider and engaging the frame to reciprocate the rider, a capping head carried by the rider, means to normally raise the lever to a substantially horizontal position, and means to limit the upward movement of the lever above said horizontal position.

3. A bottle capper comprising a frame, a rider slidable on the frame, a lever pivoted on the rider and engaging the frame to reciprocate the rider, a capping head carried by the rider, means co-acting between the rider and the lever to raise the lever and rider in position to receive the bottles beneath the capping head and with the lever in a position slightly above horizontal, and means co-acting between the rider and lever to prevent further upward movement of the lever but adapted to be released whereby said rider may have free sliding movement on the frame for adjustment to bottles of different heights.

4. A bottle capper comprising a frame, a rider slidable on the frame, a lever pivoted on the rider and engaging the frame to reciprocate the rider, a capping head carried by the rider, a member pivoted to the rider and having operative connection with the lever, means between said member and the rider to actuate the member and hold the lever and capping head out of capping position but free to move further upwardly, and means to limit the further upward movement of the lever relative to said member.

5. A bottle capper comprising a frame, a

- rider slidable on the frame, a lever pivoted on the rider and engaging the frame to reciprocate the rider, a capping head carried by the rider, means to partially raise the lever, and means movably mounted on the rider and engaging the lever to positively prevent further upward movement of the lever but adapted to be disengaged therefrom, whereby the lever may be swung upwardly further out of engagement with the frame.
6. A bottle capper comprising a frame, a rider slidable on the frame, a lever pivoted on the rider and operatively connected to the frame to reciprocate the rider, a capping head carried by the rider, and means mounted on the rider and engaging the lever to limit the upward movement of the lever, said means being mounted to be raised whereby the lever may be swung to a vertical position, whereby the rider may be freely slid on the frame to an adjusted vertical position.
7. A bottle capper comprising a frame, a rider slidable on the frame, a lever pivoted on the rider and engaging the frame to reciprocate the rider, a capping head carried by the rider, an arm pivoted to the rider and engaged with the lever, spring means normally raising the arm and lever and against the tension of which the lever and capping head are moved to capping position, and a member pivoted on the arm and adapted to engage the lever to prevent movement thereof above its raised operative position, thereby preventing accidental sliding of the rider on the frame.
8. In a bottle capper, a frame having a rack, a rider slidable thereon, a lever pivoted to the rider and having a rack segment meshing with the rack to raise and lower the rider, a spring connection between the rider and lever to raise the lever and rider and including means connected to the spring and movably connected to the rider as well as movably engaging the lever, whereby said lever is adapted to be elevated above the position in which normally supported by the spring connection to disengage the segment from the rack and permit quick adjustment of the rider on the rack bar, and means to limit the upward movement of the lever above the position in which normally supported by the spring connection.
9. In a bottle capper, a frame having a rack, a rider slidable thereon, a lever pivoted to the rider and having a rack segment meshing with the rack to raise and lower the rider, a spring connection between the rider and lever to raise the lever and rider and including means connected to the spring and movably connected to the rider as well as movably engaging the lever, whereby said lever is adapted to be elevated above the position in which normally supported by the spring connection to disengage the segment from the rack and permit quick adjustment of the rider on the rack bar, a shoulder on the lever, and a pawl carried by the spring connection adapted to engage the shoulder on the lever to prevent accidental movement of the lever above the elevated position aforesaid.
10. The combination with a bottle capper having a base, and a frame having a rack, a rider slidable over the rack, a lever pivoted on the rider and having a segment meshing with the rack, a capping head carried by the rider, a member pivoted to the rider and adapted to operatively engage the lever, spring means between the member and the rider to hold the lever elevated while maintaining operative connection between the segment and the rack, and means carried by said member to engage the lever to limit the upward movement thereof.
11. The combination with a bottle capper having a base, and a frame having a rack, a rider slidable over the rack, a lever pivoted on the rider and having a segment meshing with the rack, a capping head carried by the rider, a member pivoted to the rider and adapted to operatively engage the lever, spring means between the member and the rider to hold the lever elevated while maintaining operative connection between the segment and the rack, and means carried by said member to engage the lever to limit the further upward movement thereof and hold the member and lever rigid with each other, said means adapted to be disengaged from the lever whereby the lever may be moved further upward to permit quick sliding movement of the rider on the frame over the rack.
12. In a bottle capper, a frame, a rider slidable thereon, a lever pivoted to the rider and having operative engagement with the frame to raise and lower the rider, a spring connection between the rider and lever to raise the lever and rider, and including means connected to the spring and movably connected to the rider and lever whereby said lever may be elevated above the position in which normally supported by the spring connection to disengage the lever from the frame and permit quick adjustment of the rider on the frame, and a member between the last-named means and the lever to hold the lever thereagainst and rigid therewith to prevent upward movement of the lever independently thereof but adapted to be disengaged, whereby the lever may be swung upwardly free thereof.
13. In combination with a bottle capper having a base and a frame having a rack, a rider slidable on the rack, a lever pivoted on the rider and having a segment meshing with the rack, a capping head carried by the rider, an arm pivoted to the rider and engaged with the lever, and spring means normally turning the arm into engagement with the lever to lower the inner or segment end and raise the free or handle end thereof and against the tension of which the lever and capping head

are moved to capping position, said arm having an upwardly extending ear, a pawl pivoted to the ear and having a recess at its free end, and a shoulder on the lever for engagement by the recessed end of the pawl to check the upward movement of the lever when the capping head is out of capping position.

14. In a bottle capper, a base, a frame on the base having an upright, said upright having notches, a rider slidable on the frame over the notches and having a capping head, a lever pivoted on the rider and having means to engage with the notches for moving the rider upon actuation of the lever, a shoulder on the lever at one side, spring means to raise the lever to a point slightly above the horizontal position and also the rider and capping head out of capping position, said lever adapted to be raised further free of said spring means to disengage the first-named means from the notches, and a locking member carried by the rider and engaging the shoulder to prevent further upward movement of the lever and the rider when adjusted to a fixed position but adapted to be disengaged from the shoulder to permit further upward movement of the lever and disengagement from the notches for adjusting the rider on the upright of the frame to suit bottles of different heights.

15. A bottle capper including a frame, a rider slidable on the frame, a lever pivoted on the rider and having operative connection with the frame to reciprocate the rider by oscillation of the lever, a capping head carried by the rider, spring means between the lever and rider to normally raise and support the lever in a substantially horizontal position, means to limit the movement of said spring means to said position, said lever resting on said spring means and being free to swing upwardly from its supported position free thereof, and means to prevent further upward movement of the lever above said position in which it is normally supported.

HAROLD G. RICE.
